US00D971875S

(12) **United States Design Patent** (10) **Patent No.:** **US D971,875 S**
Bellham et al. (45) **Date of Patent:** **** Dec. 6, 2022**

(54) **HEADPHONES**

(71) Applicant: **GN AUDIO A/S**, Ballerup (DK)

(72) Inventors: **Philip Bellham**, Ballerup (DK);
Rasmus Trudslev Pedersen, Ballerup (DK);
Bill Zeng, Ballerup (DK)

(73) Assignee: **GN AUDIO A/S**, Ballerup (DK)

(**) Term: **15 Years**

(21) Appl. No.: **29/829,449**

(22) Filed: **Mar. 4, 2022**

Related U.S. Application Data

(63) Continuation of application No. 29/738,534, filed on Jun. 18, 2020, now Pat. No. Des. 951,907.

(30) **Foreign Application Priority Data**

Dec. 19, 2019 (EM) 007433701-1-5

(51) **LOC (13) Cl.** **14-01**

(52) **U.S. Cl.**

USPC **D14/205**

(58) **Field of Classification Search**

USPC D14/206, 205, 249; D29/112; 2/209;

(57) **CLAIM**

The ornamental design for a headphones, as shown and described.

DESCRIPTION

FIG. 1 is a perspective front view of the headphones.

FIG. 2 is a perspective front view thereof.

FIG. 3 is a front view thereof.

FIG. 4 is a rear view thereof.

FIG. 5 is a right view thereof.

FIG. 6 is a left view thereof.

FIG. 7 is a top view thereof; and,

FIG. 8 is a bottom view thereof.

The features shown in broken lines depict environmental subject matter only and form no part of the claimed design.

1 Claim, 8 Drawing Sheets
